Primary Examiner — Paula Greene(74) Attorney, Agent, or Firm — Birch, Stewart, Kolasch & Birch, LLP(57) CLAIM

The ornamental design for a wireless headset, as shown and described.

DESCRIPTION

FIG. 1 is a front, right side, perspective view of a wireless headset showing our new design; and

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines indicate unclaimed portion of the article that form no part of the claimed design.
